PANEL CONSTRUCTION

Filed May 2, 1927

UNITED STATES PATENT OFFICE

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK

PANEL CONSTRUCTION

Application filed May 2, 1927. Serial No. 188,222.

This invention relates to a panel construction and more especially to a panel for use in connection with motor vehicle doors, walls and the like constructed to receive and support a sash or window regulating device.

It is customary, in door and wall constructions of motor vehicles, to locate and support the sash regulating device in the well formed between the inner and outer panels or walls of the door or wall. Notwithstanding the fact that most all window regulating devices at present are so designed as to reduce the same to the smallest possible diameters nevertheless it has heretofore been impossible to materially reduce the thickness of the door or wall owing to the space required to contain and mount these window regulators. Furthermore it is now the practice to manufacture and sell the window regulators separately from the door or wall panels thus necessitating the expenditure of time necessary to mount the window regulator during the assembly of the vehicle.

It is therefore one of the primary objects of this invention to provide a panel suitable for use in motor vehicle doors and walls and to assemble therewith the window regulator. The invention contemplates a panel construction including a recess or depression formed therein, a portion of which is designed to receive the operating mechanism of the sash regulating device whereupon the adjacent wall of the panel constitutes a portion of the housing for this operating mechanism, the remaining portion being formed by a plate or cover member secured to the panel over the recess. The invention also contemplates the utilization of other depressions or a portion of the main depression in the panel for the purpose of guiding the sash engaging element. With such a construction the thickness of the door or wall may be materially reduced owing principally to the fact that the usual housing for the operating mechanism is eliminated as well as the guides for the travelling sash engaging member together with the supports for these guides. Another advantage of this construction is that the window regulator and sash may, by the provisions of this invention, be manufac-

tured, sold and installed in a door or wall construction, as a unit.

The invention has also among its objects to simplify, render more efficient and improve generally devices of this character and the several objects and advantages will be made more apparent as this description proceeds, especially when considered in connection with the accompanying drawings, wherein

Figure 1 is an elevational view of the inside of a door including a panel constructed in accordance with this invention;

Figure 2 is an enlarged fragmentary elevational view of the other side of the panel showing the sash regulating device associated therewith;

Figure 3 is a vertical sectional view taken substantially on the plane indicated by the line 3—3 in Figure 1;

Figure 4 is a sectional view taken substantially on the plane indicated by line 4—4 in Figure 1;

Figure 5 is a fragmentary sectional view taken substantially on the plane indicated by line 5—5 in Figure 2; and

Figure 6 is a sectional view taken substantially on the plane indicated by line 6—6 in Figure 2.

Referring now particularly to the drawings wherein like reference characters indicate like parts, it will be noted that the invention is illustrated as associated with a door including a frame 10 having recesses or grooves 11 within which the glass closure 12 is adapted to slide. As is customary, the door will include an outer panel 13 and, in the present disclosure, an inner panel 14 constructed in accordance with this invention.

The type of window regulator herein illustrated is shown and described in detail in United States Letters Patent 1,537,004 granted May 5, 1925, to G. A. Carlson. However, as this description proceeds it will be readily apparent to those skilled in this art that the invention is not limited in its uses to the particular type of sash regulating device illustrated but may be employed with equal facility and utility with other types of window regulators. However, the sash regulating device illustrated herein and in the

said patent includes an operating mechanism indicated generally by the reference character 15 and a chain or sash engaging element 16 which carries the roller 17 at one end thereof adapted to engage the lower edge of the glass closure 12 for raising and lowering the same. The operating mechanism 15 which operates the chain 16 is controlled by means of a handle 18.

19 It has been customary heretofore to mount the operating mechanism 15 within a housing upon which certain rotatable parts thereof are supported. The present invention, however, contemplates forming the panel 14 15 with a recess or depression 19 pressed outwardly from the general plane of the panel. In one portion of this recess the operating mechanism 15 is arranged and this portion of the recess has associated therewith a cover 20 plate or member 20 which may be conveniently secured to the panel at spaced points by means of lugs or ears 21. Thus the adjacent walls of the recess 19 and the cover member 20 constitute a housing for enclosing and supporting the operating mechanism 15. The sides of the recess 19 are arranged preferably in spaced parallel relation and associated therewith are guide strips or members 22 which may be welded or otherwise secured to 25 the bottom of the depression 19. These guide members cooperate with the adjacent walls of the depression to form guide-ways for the chain or sash engaging member 16.

From the foregoing it will be readily apparent that the thickness of the door or wall 25 may be materially reduced and that furthermore the sash regulating device may be permanently associated with the panel when the latter is manufactured and sold and installed 40 as a unit.

While an embodiment of the invention has been illustrated and described herein somewhat in detail it will be readily apparent that various modifications may be made without 45 departing from the spirit and scope of the invention and to this end reservation is made to make such changes as may come within the purview of the accompanying claims.

What I claim as my invention is:

50 1. The combination with a sash regulating device including an operating mechanism, of a panel for doors, walls and the like adapted to support the operating mechanism and a plate member secured to said panel and 55 constituting with the adjacent portion thereof of a housing to enclose said operating mechanism.

2. The combination with a sash regulating device including an operating mechanism 60 and a sash engaging element, of a panel for doors, walls and the like, said panel having a depression therein, a plate member secured to said panel and extending over and cooperating with said depression to form a housing 65 to support and enclose said operating

mechanism and guide members secured to said panel and cooperating with said depression to form guideways for said sash engaging element.

3. The combination with a window lifter 70 mechanism, of a panel for doors, walls and the like, said panel having a recess to receive said mechanism and a cover closing said recess, said cover and panel forming a housing therefor.

4. The combination with a sash regulating device including operating mechanism, of a panel having a recess formed therein adapted to receive said mechanism and to constitute a part of a housing therefor and a cover 80 member secured to said panel over said recess and constituting a complementary housing part.

5. The combination with a sash regulating device including operating mechanism 85 and a travelling member, of a panel formed with a recess therein, a cover plate secured to said panel and cooperating with a part of said recess to form a housing for said mechanisms and guide members secured to said 90 panel and cooperating with the remainder of said recess to form a guideway for said travelling member.

6. The combination of a frame having an opening and a chamber adjacent said opening, a metallic panel forming one wall of said chamber and having a depression therein, a movable closure for the opening, an actuating mechanism for said closure located in said depression, and a plate member secured to said panel and cooperating with said depression in forming a housing to enclose said actuating mechanism.

7. The combination of a frame having an opening and a chamber adjacent said opening, a metallic panel forming one wall of said chamber and having a depression therein, a movable closure for the opening, a closure regulating device including operating mechanism and a travelling member, said operating mechanism and travelling member being located in said depression, a cover plate secured to said panel and cooperating with a portion of said depression to form a housing for said mechanism, and guide members 115 also secured to said panel and extending over said travelling member and cooperating with said depression to form a guideway for said travelling member.

In testimony whereof I affix my signature. 120
WILLIAM S. PRITCHARD.
